UNITED STATES PATENT OFFICE.

KENNETH J. TOBIN AND WILLIAM W. DARROW, OF CHICAGO, ILLINOIS, ASSIGNEES TO
CAMEL COMPANY, OF CHICAGO, ILLINOIS, A CORPORATION OF ILLINOIS.

CAR-DOOR SUPPORT.

Application filed December 15, 1924. Serial No. 755,824.

This invention relates to a car door support.

Under existing practice, car doors are supported upon a pair of spaced rollers either at the bottom or at the top. It has been found in practice that no matter how perfectly a car door would be hung on a car, a short trip would cause a settling or distortion of parts so that it became very difficult to operate the door.

It is an object of this invention to overcome this objection in the provision of a single roller support for a car door that may support the door either at the top or bottom, in balanced position, that allows a limited pivotal or tilting movement of the door in its plane to assist in the operation thereof and to free it of any binding that might occur.

It is a further object of this invention to provide a novel form of hanger that can be manufactured by the drop forging process and assembled without the use of bolts or rivets and that will support the door without putting the attaching bolts in shear.

With these and other objects in view which will become more apparent in the following description and disclosures, this invention comprises the novel structure and combinations hereinafter described and more particularly pointed out and defined in the appended claims.

In the accompanying drawings which illustrate a preferred embodiment of this invention and in which similar reference numerals refer to similar features in the different views:

Figure 1 is a fragmentary broken elevational view of a car door showing this invention applied thereto.

Figure 2 is an enlarged view taken upon the line II-II of Figure 1, with parts removed.

Figure 3 is a plan view of the anti-friction rollers on the door.

Figure 4 is a plan view of a modification of anti-friction roller construction for the door.

Figure 5 is an enlarged elevational view of the main door hanger.

Figure 6 is an enlarged side elevational view of the main door hanger.

Figure 7 is an enlarged plan view of the hanger in disassembled form illustrating the assembling thereof.

As shown on the drawings:

In referring to the drawings which illustrate an embodiment of this invention it will be observed that there is shown a door hanger comprising a forged casting 1 having an apertured flat face 2 for attaching the same to a door. Above the flat face 2 there is a shoulder 3 which engages under the web of the Z bar 17 of the door for supporting the same. At the outer end of the shoulder there extends the vertical roller supporting arm 4. The outer surface of the hanger is provided with a plurality of strengthening ribs 5. The upper end of the roller arm terminates in a transverse plate 6 having inwardly projecting spaced bosses 7 to provide a space therebetween for the reception of a roller 8. These bosses terminate in reduced rivet shanks 9. The plate 6 is provided with a polygonal socket 10 for receiving the polygonal end 11 of the roller supporting axle. A plate 12, likewise provided with a polygonal socket 13 adapted for fitting over the opposite end 11a of the roller supporting axle, is provided. This plate has a pair of spaced apertures 14 for receiving the rivet shanks 9.

In assembling this hanger the roller 8 is positioned upon its axle and then placed between the bosses 7 with the polygonal end 11 of the axle engaging the socket 10. The plate 12 is then positioned so that the socket 13 will engage over the polygonal end 11a of the roller axle and the apertures 14 will engage over the rivet shanks 9. The rivet shanks 9 are then swaged over the plate 12 for combining the plate with the casing.

This hanger is adapted to be centrally supported at the top of a car door 15 for suspending the same in balanced position, the shoulder 3 engaging under the web of the Z bar 17 for taking the shear off the attaching bolts of the hanger. The roller 8 travels upon the usual track 16. As the upper edge of the door is spaced below the track, the door can pivot upon the roller 8 or in other words can be tilted in its plane until it strikes the track. In operating the door, the upper surface adjacent one end thereof is usually elevated into engagement with the lower surface of the track and a good deal of friction would be engendered. To overcome this friction, anti-friction elements are interposed between the upper ends of the door and the track. In referring to Figure 2 it will

- be noted that the upper border of the door consists of the Z bar 17 and adjacent each end of the web of the Z bar there is secured a casting 18 having an upstanding arcuate lug 5 19 to reduce friction and opposed to the upstanding flange of the Z bar 17. A short shaft 20 integral with said lug extends into an aperture in said flange and an anti-friction roller 21 is journaled upon said shaft. 10 These anti-friction rolls are normally spaced a short distance below the track to provide a limited tilting movement.

In the modification shown in Figure 4 the casting 18^a is similar to the casting 18 except 15 that it contains a vertical support for an anti-friction roll 22 which is adapted for rolling along the inner surface of the depending flange 16^a of the track 16 for guiding the door in its movement, the upstanding flange 20 of the Z bar 17 being cut away to allow the roller to project therethrough. The casting 18^a in connection with the Z bar supports the anti-friction roll 21 as in the case of the structure shown in Figure 3.

25 From the foregoing it will be apparent that a novel form of door support has been provided which is assembled without the use of bolts or rivets and which is located so as to balance the door; however allowing the same 30 to be slightly tilted to overcome any binding and for swinging the center of gravity for assisting the operation thereof.

We are aware that many changes may be made, and numerous details of construction 35 may be varied through a wide range without departing from the principles of this invention.

tion, and we therefore do not purpose limiting the patent granted hereon, otherwise than necessitated by the prior art.

We claim as our invention:

1. In a door hanger, a metal member having an attaching means and a roller supporting head provided with spaced bosses terminating in rivet shanks, a member secured to said shanks and a roller supported 45 between said head and member.

2. In a door hanger, a member having a roller receiving recess, with a socket in the wall thereof, a plate member swaged to said member and having a socket, a shaft supported in said sockets and a roller supported on said shaft. 50

3. In a door hanger, a member having spaced projections terminating in reduced portions, a plate member attached to said reduced portions, said plate and member having opposed sockets, a shaft supported by said sockets and a roller mounted upon said shaft. 55

4. The combination with a door having a 60 projecting flange at one margin and a hanger therefor having a horizontal seat engaging one side of the flange, a portion extending in one direction beyond said seat for attachment to the door, an arm extending in the opposite direction from said seat, and a roller mounted on said arm. 65

In testimony whereof we have hereunto subscribed our names.

KENNETH J. TOBIN.

WILLIAM W. DARROW.
